UNITED STATES PATENT OFFICE.

FRANK E. CARTIER, OF WINSLOW, WASHINGTON.

FASTENING FOR KNOCKDOWN FURNITURE AND THE LIKE.

1,078,186.

Specification of Letters Patent. Patented Nov. 11, 1913.

Application filed November 21, 1912. Serial No. 732,706.

To all whom it may concern:

Be it known that I, FRANK E. CARTIER, a citizen of the United States of America, and a resident of the city of Winslow, in the county of Kitsap and State of Washington, have invented certain new and useful Improvements in Fastenings for Knockdown Furniture and the like, of which the following is a specification.

10 My invention has particular reference to an improved provision for attaching or connecting together separable parts of articles of the knockdown type, and has for its primary object to provide such a construction 15 which is simple, comparatively inexpensive to manufacture, and permits of the parts being readily assembled and disassembled in an efficient manner.

Briefly described, the invention comprises 20 companion normally interlocking parts adapted to be secured to the meeting or opposing surfaces of the furniture parts, together with suitable locking devices which insure of the fastening parts being held in 25 their normal or operative relation.

I have shown my invention as applied to a table structure which latter has embodied therein corner braces. In such a structure I employ a plurality of fasteners disclosing 30 the invention in two distinct forms.

Another object of the invention resides in a novel arrangement of adjacent fastening devices, whereby greater rigidity in the set up furniture structure is insured.

35 Other objects will be set forth as my description progresses and those features of construction, arrangements and combinations of parts on which I desire protection, succinctly defined in my annexed claim.

40 Referring to the accompanying drawings wherein like numerals of reference indicate like parts throughout: Figure 1 is a fragmentary top plan of the table equipped with my invention, parts being broken away.

45 Fig. 2 is a bottom plan thereof with one of the legs broken away. Fig. 3 is a fragmentary perspective of one of the side rails and the legs, the rail being illustrated as removed from the leg. Fig. 4 is a fragmentary 50 perspective illustrating more particularly the connecting device employed for making the brace fast to a side rail, the fastening members being disengaged, and Fig. 5 is a vertical section taken on line 5—5 of Fig. 1.

55 Referring to the drawings by numerals of reference, 1 indicates legs, and 2 side

rails, the latter being arranged in substantially rectangular relation and having their ends fastened to adjacent faces of the legs 1 by devices 3 to form a suitable frame. Devices 3 being identical in construction, a description of one will suffice. This comprises a female member 4 having a boss 4' on its rear face which is set into a suitable seat provided therefor in leg 1 and secured 65 therein, as by screws 10, as clearly shown in Figs. 1 and 3. Member 4 which is substantially rectangular is provided with an angular edge flange 4'', this extending along the upper and lower and outer vertical edges 70 thereof to form an interlocking part with which a flange-like extension 5' of a male member 5 normally engages.

Member 5 comprises a hollow body fitted on the end portion of rail 2 and secured 75 thereto by screws 11, and having its projecting forward end portion provided with flange 5', this flange extending on three sides of the body in corresponding arrangement to the flange 4'' of member 4. Body 5 is 80 further provided with a removable side wall 5'', the same being formed on its forward edge with an eye extension 6 which is adapted to normally fit snugly between similar eye extensions 7 of member 4 and receive a 85 suitable locking pin 8.

By forming member 5 with a removable inner side wall 5'', the latter can if desired be first connected by locking pin 8 to member 4, and then fastened, as by screws 9, to 90 side rail 2 after member 5 has been inserted in the member 4 thereby insuring of the proper registration of eye extensions 6 and 7, as will be readily understood. To release the parts after they have been once assembled in this manner it is obviously only necessary to remove pin 8 and then force the side rail in an inward direction.

Reference numeral 12 indicates corner braces which are connected to rails 2 by connecting devices 13. Connecting devices 13 being identical in construction, a description of one will suffice. This comprises a male member 14 having a hollow body which receives one end portion of the brace 12, and 100 provided on its side and lower edge portions with a flange 14' for interlocking engagement with an angular flange 14'' of a female member 15.

Female member 15 comprises a substantially rectangular plate provided on its outer face with a boss 15' which is seated in a

suitable cut-out of rail 2 and secured there-to, as by screws, as shown. Flange 14" consists of an edge extension of member 15 and extends along the side and lower portions 5 thereof. By this construction member 14 is inserted into member 15 through the open upper end of the latter, and when properly seated, eye extensions 16 thereof snugly straddle an eye extension 17 of the member 15 in position for ready insertion of a locking pin 18.

The particular arrangement of devices 3 and 13 insures of the rails 2 and legs 1 being firmly united.

15 Reference numeral 19 indicates a table top provided with angle plates 20 which are bolted, as at 21, to braces 12.

To knock down the structure, top 19 is first removed, following which ready access is had to locking pins 8 and 18. These 20 being removed, braces 12, and then side rails 2 can be readily separated, as is apparent.

Having thus described my invention what I claim as new, and desire to secure by Let-

ters Patent of the United States of America, 25 is:—

In a device of the character described, the combination with separate parts of furniture or the like to be connected, a fastening for said parts comprising male and female members, the male member having a hollow portion provided with a flange receivable by the female member and a removable side wall formed at one end with an eye, said female member having an eye 35 adapted to register with the eye of the male member, and means insertible through the eyes of the members for locking the latter together, said removable side wall being reinforced by the hollow body of the male 40 member on any movement tending to separate the aforesaid members.

Signed at Seattle, Washington, this 16th day of November 1912.

FRANK E. CARTIER.
